CLAIM

We claim the ornamental design for a contact grill, as shown and described.

DESCRIPTION

FIG. 1 is a top frontal perspective view of a first embodiment of a contact grill according to our new design;

FIG. 2 is a front view of the contact grill shown in FIG. 1;

FIG. 3 is a back view of the contact grill shown in FIG. 1;

FIG. 4 is a left side view of the contact grill shown in FIG. 1;

FIG. 5 is a right side view of the contact grill shown in FIG. 1;

FIG. 6 is a top view of the contact grill shown in FIG. 1; and,

FIG. 7 is a bottom view of the contact grill shown in FIG. 1.

The broken lines in the drawings are for illustrative purposes only and form no part of the claimed design.
